UNITED STATES PATENT OFFICE.

TURNER MILLER, OF FAYETTEVILLE, ARKANSAS.

OILING DEVICE.

Application filed April 7, 1926. Serial No. 100,380.

My present invention has reference to a lubricating system between journals and bearings therefor and is particularly adapted for use in connection with the running gear 5 of an automobile.

An object is the provision of means whereby a lubricant can be pocketed and fed between movable or revoluble parts which will dispense with the employment of pressure devices for forcing said lubricant between said parts.

A further object is the provision of a means for this purpose that is of a comparatively simple construction, which will effectively hold the lubricant pocketed until all of said lubricant is fed to the parts to be lubricated thereby, and further wherein all surplus lubricant which may have a tendency to harden or any foreign substances 20 which may have been let in the well or pocket for the lubricant, will be withdrawn therefrom when a new supply of lubricant is required.

To the attainment of the foregoing, the improvement resides in the novel features 25 of construction, combination and operative association of parts, a satisfactory embodiment of which is illustrated by the accompanying drawings.

In the drawings:

Figure 1 is an elevation partly in section illustrating my improvement employed in connection with the spindle bolt and the front axle of an automobile.

Figure 2 is a similar view but illustrating the improvement in connection with the spring shackle bolt of an automobile.

Figure 3 is a sectional view on the line 3—3 of Figure 2.

Figure 4 is a sectional view on the line 4—4 of Figure 2.

Figure 5 is a detail longitudinal sectional view showing the improvement provided with a lubricant cup.

Figure 6 is a perspective view of the auger member employed in connection with the constructions illustrated in Figures 1 to 4.

Figure 7 is a view of the auger member employed in the construction illustrated in Figure 5.

Figure 8 is an end view of the auger as shown in Figure 7.

In the drawings and with reference to Figure 1 thereof, the numeral 1 designates 55 the spindle bolt which is received through the spindle body bushing 2 on one end of

the spindle 3 for the front axle of an automobile, the forked end of the front axle through which the bolt 1 passes being indicated by the numeral 4.

In carrying out my invention I bore a round opening partly through the bolt 1, from the upper headed end thereof. The opening, indicated by the numeral 5, is eccentric with respect to the axial plane of 65 the bolt, the said bolt being notched, as at 6, in a line inwardly of the bottom wall provided by the opening 5. The opening 5 provides a lubricant well and screwed in the said opening at the outer and headed 70 end of the bolt 1, there is a sleeve 7. The sleeve is designed to have arranged thereover a cap member 8 and this cap member carries an auger 9 which is adapted to be received in the lubricant well. Of course, 75 a lubricant is fed into the well before the auger is arranged therein and the cap 8 is indented to provide a spring tooth 10 to be received in a depression 11 in the sleeve 7.

The auger is in the nature of a tubular member which is centrally slotted throughout its length to a point at or adjacent its connection to the cap 8. One of the arms of the auger may be of a greater length than the other and the said longer end being 80 shaped to provide a cutting element or bit 12.

The cap 8 effectively closes the oil well, and by turning the said cap the bit end 12 as well as the sharpened edges of the auger will scrape the well and remove therefrom 90 any lubricant which has adhered thereto when the said auger is removed from the well.

With a construction as just described it 95 will be apparent that the employment of high power grease guns for lubricating the movable parts of a machine will be effectively dispensed with.

In Figures 2, 3 and 4, I have illustrated my improvement in connection with the bolt 13 for a spring shackle 14. In this instance the bolt 13 is formed from one of its ends with a round opening that provides an oil well 15, the said bolt having a notch 16 which communicates with the well. The well is arranged eccentric with respect to the axial center of the bolt. The bolt has screwed in the opening 15 an outwardly extending sleeve 17 provided on its top face with an opening 18. Arranged over the 105 sleeve there is a cap member 19 that carries an auger 20 of a similar construction to the

auger above described. The cap 19 has an opening 21 therethrough adapted, when the cap is turned, to register with the opening 18, and through these openings a lubricant 5 may be poured which, of course, will enter the well and lubricate the elements 13 and 14. The cap is also formed with an indenture providing a spring tooth 22 which is de- 10 signed to be received in the opening 18 when the cap is turned to close the said opening 18. By turning the cap 19 the bore of the lubricant well 15 will be scraped and in this instance the cap and auger are only removed from the well when the scraping of such 15 well is desired.

In Figures 5, 7 and 8 I have illustrated a further modification. In this instance a bolt or journal member 23 is provided with a well 24 disposed to one side of the axial center of the said member 23, there being a notch 25 which communicates with the well. The bolt member is received in a suitable bearing 26 and screwed in the well; at one 20 end of the member 23, there is a lubricant receptacle 27. Screwed on the receptacle 27 there is a lubricant cap or cup 28 that carries an auger 29. In this instance, the auger is in the nature of a metal plate or bar having its free end sharpened to provide the same with 25 a bit 30 and being provided from its edges or its opposite sides with round auger portions 31. This construction is employed

when a heavy lubricant is fed between the stationary and movable parts.

The simplicity of my construction and the 35 advantages thereof will, it is thought, be perfectly apparent to those skilled in the art to which such invention relates when the foregoing description has been read in connection with the accompanying drawings. 40

Having described the invention, I claim:

1. The combination with a bearing having an oil well therein, provided with a passage to communicate with an element journaled on the bearing, of a means for feeding oil into the well and for scraping oil therefrom, comprising an auger received in the well and contacting with the walls thereof. 45

2. The combination with a bearing having an oil well therein provided with a passage to feed a lubricant onto an element journaled on the bearing, of a means for feeding a lubricant into the oil well and for scraping the same therefrom, said means comprising an auger received and revoluble in the well, said 50 auger including a straight portion whose edges contact with the wall of the bore of the well and a curved portion which also contacts with the bore of the well, and the end of the auger received in the well being 55 sharpened. 60

In testimony whereof I affix my signature.

TURNER MILLER.
